(74) Attorney, Agent, or Firm — Brinks Gilson & Lione

(21) Appl. No.: **29/444,225**

(57) **CLAIM**

(22) Filed: **Jan. 28, 2013**

I claim the ornamental design for an electric hair clipper, as shown and described.

(51) LOC (10) Cl. **28-03**

DESCRIPTION

(52) **U.S. Cl.**

USPC **D28/53**

(58) **Field of Classification Search**

USPC D28/49-54, 44-48; 30/34.05, 32, 34.1, 30/34.2, 43-43.92, 526-527, 44-45, 341, 30/272.1, 226-227, 231, 233-233.5, 537, 30/539-540

See application file for complete search history.

(56) **References Cited**

FIG. 1 is a front perspective view of an electric hair clipper of the present invention;
FIG. 2 is a rear perspective view thereof;
FIG. 3 is a front view thereof;
FIG. 4 is a rear view thereof;
FIG. 5 is a first side view thereof;
FIG. 6 is a second side view thereof;
FIG. 7 is a top view thereof;
FIG. 8 is a bottom view thereof;
FIG. 9 is a cross-section view taken along the line 9 of FIG. 3; and,
FIG. 10 is an enlarged view taken along the line 10 of FIG. 9. The broken lines illustrate portions of the article and form no part of the claimed design.
